UNITED STATES PATENT OFFICE.

ALFRED E. LARSEN, OF CHICAGO, ILLINOIS, ASSIGNOR TO UNIQUE LAMP & CASTING COMPANY, A COPARTNERSHIP CONSISTING OF ALFRED E. LARSEN AND LAWRENCE LARSEN, OF CHICAGO, ILLINOIS.

DESIGN FOR AN ELECTRIC CEILING FIXTURE.

Application filed May 10, 1928. Serial No. 26,618. Term of patent 3½ years.

To all whom it may concern:

Be it known that I, ALFRED E. LARSEN, a citizen of the United States, residing at Chicago, in the county of Cook and State of Illinois, have invented a new, original, and ornamental Design for an Electric Ceiling Fixture, of which the following is a specification, reference being had to the accompanying drawing, forming part thereof.

Figure 1 is a plan view of the fixture illustrating the design only a portion of the complete ornamentation being shown.

Figure 2 is merely a diagrammatic view of Figure 1.

I claim,

The ornamental design for an electric ceiling fixture as shown.

ALFRED E. LARSEN.
